DESIGN FOR A PHOTOGRAPHIC EXPOSURE METER CASE

Malcolm G. Townsley, Chicago, Ill., assignor to
The Bell & Howell Company, Chicago, Ill., a
corporation of Illinois

Application April 24, 1940, Serial No. 91,898

Term of patent 14 years

To all whom it may concern:

Be it known that I, Malcolm G. Townsley, a citizen of the United States, residing at Chicago, in the county of Cook and State of Illinois, have invented a new, original, and ornamental Design for a Photographic Exposure Meter Case, of which the following is a specification, reference being had to the accompanying drawing, forming a part thereof.

In the said drawing—

Figure 1 is a side elevation of a photographic exposure meter case embodying my invention and showing it in expanded condition;

Figure 2 is another side elevation of the same taken normal to the elevation of Figure 1;

Figure 3 is an end elevation of the same taken from the left of Figures 1, 2 and 4; and

Figure 4 is a side elevation similar to Figure 1 and showing the case in contracted condition.

I claim:

The ornamental design for a photographic exposure meter case, as shown.

MALCOLM G. TOWNSLEY.
